UNITED STATES PATENT OFFICE.

ARTHUR R. BLEWETT, OF SPOKANE, WASHINGTON.

DESIGN FOR A STREET-ELECTROLIER.

42,725.

Specification for Design.

Patented July 9, 1912.

Application filed February 15, 1912. Serial No. 677,870. Term of patent 14 years.

To all whom it may concern:

Be it known that I, ARTHUR R. BLEWETT, a citizen of the United States, residing at Spokane, in the county of Spokane and State of Washington, have invented a new, original, and ornamental Design for a Street-Electrolier, of which the following is a specification, reference being had to the accompanying drawing, forming part thereof.

The figure is a view in elevation of a street electrolier showing my new design.

I claim:

The ornamental design for a street electrolier, as shown.

ARTHUR R. BLEWETT.

Witnesses:

W. S. GILBERT,
HUBERT P. SUING.
